VOLUME EXPANDER

Georges Gadbois, Sweetsburg, Quebec, Canada

Application April 17, 1943, Serial No. 483,533

6 Claims. (Cl. 179—171)

The present invention relates to the electrical reproduction of sounds and, more particularly, to an improved circuit of volume expanders.

As is well known, it is sometimes desirable to compress the range of intensities of transmitted, or recorded, sounds to render said sounds acceptable to the medium being used for transmission or recording. The reproduction of said compressed sounds, or signals, is thereafter effectuated through means capable of restoring the range to its original value, and provided with so-called volume expanders.

Such an expander is, generally speaking, an electrical device energized in accordance with the volume level of the reproduced sounds, and adapted to actuate, correspondingly, the amplifying gain of the sound reproducer.

In practice, it is usual to rectify a small portion of the reproducer output voltage, and to apply this rectified component as a grid bias affecting the first amplifying stage or stages of the reproducer.

But, experience has shown that operating on the grids of the first stages introduces disturbances in the system, such as overloading and parasitic impulses, which affect the final rendition of the sounds or signals.

The present invention has been conceived to avoid the disadvantages noted above and, therefore, the objects may be stated as follows:

The main object of the invention resides in the provision of means for improving the efficiency of volume expanders.

Another object is the provision of a circuit arrangement for volume expanders, whereby means other than the first amplifying tube are used for volume expansion.

A further object is the provision of a volume expander capable of high fidelity reproduction.

Still another object contemplates a volume expander of the character described which is highly flexible of application and easily controlled.

A still further object provides for an expander of the character described which is relatively inexpensive to set up and of reliable operation.

Other objects and advantages of the invention will become apparent as the description progresses.

For purposes of illustration, and as examples, two possible embodiments of the invention are shown in the annexed diagrammatical drawing, wherein:

Figure 1 is a schematic representation of the expander connections with respect to an audio amplifier;

Figure 2 is a similar representation of a pre-

ferred embodiment involving separate amplifying channels, and

Figure 3 is a simplified basic circuit of the expander proper.

Referring to the drawing, wherein similar reference characters represent corresponding parts throughout, the representation is that of a reproducer consisting of an amplifier having input and output terminals and to which the expander 5 of the invention is connected. In order to simplify the representation, and since the components of the amplifier are conventional, well known and may comprise any of various circuits, the "block" system of illustration has been used. Each of said blocks is therefore lettered according to its general function and disposed in the circuit according to its relative position therein.

In Figure 1, the simplest arrangement is shown which consists of a first amplifier, or pre-amplifier as it is sometimes called, an intermediate amplifier adapted to raise the pre-amplified signal, or sounds, to higher levels, and a power amplifier the output of which may be connected to a transmission line or sound emitting means.

All said amplifiers are thermionically operated and are assumed to include their own sources of actuating potential although, in practice, they are all connected to a common source or power pack.

The expander 5 is connected to the input terminals, as shown in Figure 3, to apply the received signal across the grid 7 and cathode 8 of a tube 6 for amplification purposes. But, the plate 9 of said tube is not connected to any source of constant potential and, accordingly, the said tube 6 should be inoperative normally.

In order to render tube 6 active, it is evident that a positive potential must be applied to the plate and, for that purpose, a portion of the output voltage of the power amplifier is bled therefrom, rectified through the rectifier 10 and applied to the plate 9 through a suitable plate load. Thus, under operative conditions, the potential applied to plate 10 shall be a variable potential of positive polarity, corresponding in all respects to the envelope of the pulsating currents present in the output of the power amplifier.

Consequently, the dynamic characteristics of the tube 6 are affected in accordance with the variations occurring in the positive potential applied to its plate 9. As a result, the amplifying properties of said tube are also variable in direct proportion to the peaks present in the power amplifier output.

Therefore, the tube 6 amplifies the signal of the input terminals in a variable manner, depending on the characteristics of the signal it-

self. If the plate 9 of tube 6 is connected, through condenser 11, to the input of the intermediate amplifier, expanded impulses shall be superposed over the signal being amplified therein and will similarly affect the output of the power amplifier. The result is, consequently, an amplified signal expanded in a ratio strictly proportional to the characteristics of the signal itself.

The object of the arrangement just described is to avoid using the first amplifying tube for expansion purposes, as is the common practice. The reasons for avoiding using said first tube are motivated by the fact that the permissible potential variations, in a grid circuit, are strictly limited, and complicated, by the grid bias voltage necessary for proper operation; the incoming signal, therefore, is generally all that the pre-amplifier can accept without distortion. When, over these signal impulses, an expanded image thereof is superposed, the combination is generally more than can be handled, unless extreme care is used in feeding back only a very feeble, and ineffective, expanded image. Consequently, the use of a separate tube according to the invention, which tube is plate-controlled, is a complete solution to the problem set forth above, since even the ordinary so-called "all purpose" tubes are operable with plate voltages varying from a few volts to 250 or more.

As a further refinement against grid distortion, a second embodiment of the invention is shown in Figure 2, wherein a separate volume expanding channel is shown. This arrangement is preferred, because the expanded signal impulses are not superposed above those amplified in the intermediate amplifier where, if the design is not generous, distortion may still occur should the expansion be allowed to overload same.

Therefore, the expanded signal from expander 5 is amplified directly through a separate amplifying channel including intermediate and power amplifiers. The non-expanded signal impulses are pre-amplified, as usual through the first amplifier and, thereafter, raised to a level, suitable for proper expander operation, by means of a simple voltage amplifier 12, which voltage amplifier is solely designed for raising the potential of the signal impulses. Due to the fact that the current necessary to operate the expander is slight, said voltage amplifier may be constituted of simple elements and does not necessitate power tubes or the like.

Thus, both the signal impulses and the expanded impulses being handled through separate channels, the possibilities of distortion are reduced to a minimum and, of course, the pre-amplifier is relieved of the task of amplifying both the signal and its expanded image.

From the foregoing, it should be apparent that the present invention represents an advance of the art: through the intermediary of simple means effective expansion of compressed signals is easily achieved with good fidelity. Furthermore, relatively more expansion is possible, with given apparatus, than is feasible using the conventional system described previously and with the same permissible percentage of harmonics.

Finally, it should be evident that better control of the quality of reproduced sounds is possible, due to the separation of amplified signal and its expanded image into separate channels at the input.

Although, for purposes of simplification, the

drawing shows in Figure 3 a triode as the expander tube 6, it is pointed out that in practice tetrodes are preferable since they are better adapted to prevent disturbances and other difficulties due to the inter-electrode capacities.

It is to be understood that various changes in the arrangement of elements can be made, without departing from the spirit of the invention or the scope of the subjoined claims.

Having thus described my invention, I claim:

1. A signal control method of the character described, comprising amplifying a periodically-varying-components signal, simultaneously applying said signal to the grid of a separate thermionic tube, rectifying a portion of the amplified signal impulses to obtain a direct current potential varying in accordance with the intensity of the signal impulses, using said potential as the sole plate voltage source for the thermionic tube so as to cause the dynamic characteristics thereof to change in conformity with the plate voltage, and thereafter amplifying and reproducing the expanded signal amplified by the said tube.

2. A volume expander of the character described including a signal source and signal amplifying means, comprising a separate thermionic tube having its grid connected to the source, and means for applying to the plate of said tube a D. C. operating potential rectified from the signal amplifying means and varying in accordance with the intensity of the signal component peaks, whereby the signal amplified by said tube is expanded in accordance with the characteristics of the signal itself.

3. In a signal control system having a signal source and signal-amplifying means, signal expanding means having a separate thermionic tube connected to the source and devoid of fixed plate potential, means for applying to the plate of said tube a potential rectified from the output of the signal-amplifying means, and means for amplifying and reproducing the expanded signal appearing on the plate of said tube.

4. In an amplifier having input and output and the input of which is connected to a signal source, a separate expander tube connected to said source and including at least three elements of which one is a plate devoid of fixed plate voltage, a diode rectifier between said plate and the amplifier output, and means for amplifying and reproducing the signal appearing on the plate of the expander.

5. In a signal control method wherein signals from a source are amplified by a thermionic amplifier, causing rectification of a portion of said amplified signal to obtain a pulsating D. C. potential, using said potential as sole plate voltage for a separate thermionic amplifier, applying from the source the signals to said separate amplifier, and thereafter causing amplification and reproduction of the signals issuing from said separate amplifier.

6. A method of the character described, comprising the thermionic amplification of signals from a source in the usual manner, simultaneously applying the signals to a separate independent thermionic tube devoid of normal plate operating potential, causing operation of said tube by applying to the plate thereof a pulsating D. C. current rectified from a portion of amplified signals, and thereafter amplifying separately the signals amplified by the independent tube.

GEORGES GADBOIS.
